UNITED STATES PATENT OFFICE

157,983

ARABIC ALPHABET

Nasri Najib Khattar, New York, N. Y.

Application October 3, 1947, Serial No. 141,748

Term of patent 14 years

(Cl. D64—12)

To all whom it may concern:

Be it known that I, Nasri Najib Khattar, a citizen of the Republic of Lebanon and a resident of New York, in the county of New York, State of New York, have invented a new, original, and ornamental Design for an Arabic Alphabet, of which the following is a specification, reference being had to the accompanying drawing, forming a part thereof.

The drawing illustrates face views of an Arabic alphabet, showing my new design.

I claim:

The ornamental design for an Arabic alphabet, substantially as shown.

NASRI NAJIB KHATTAR.
